UNITED STATES PATENT OFFICE.

ELI M. BUECHELE, OF JUBILEE, IOWA.

FENCE-POST AND WIRE-FASTENER.

1,000,774.

Specification of Letters Patent. Patented Aug. 15, 1911.

Application filed May 6, 1911. Serial No. 625,465.

To all whom it may concern:

Be it known that I, ELI M. BUECHELE, a citizen of the United States, residing at Jubilee, in the county of Blackhawk and State of Iowa, have invented certain new and useful Improvements in Fence-Posts and Wire-Fasteners, of which the following is a specification, reference being had to the accompanying drawings.

My invention relates to new and useful improvements in metallic fence posts and more particularly to means for fastening fence wires in position thereon and the object of the invention is to provide a post of this character having a plurality of ears or tongues in vertical alinement thereon between which the wires are adapted to extend.

A further object of the invention resides in forming these ears or tongues by striking up portions of the body of the post and providing said tongues with alining openings.

A further object of the invention is to provide a plurality of retaining keys or pins adapted for insertion through the pairs of tongues to retain the wires therebetween, and a still further object resides in providing means at the ends of said pins for retaining the same in position on the post.

With these and other objects in view, my invention consists in the novel features of construction, combination and arrangement of parts as will be hereinafter referred to and more particularly pointed out in the specification and claim.

In the accompanying drawing forming a part of this application, Figure 1 is a detail perspective of a post constructed in accordance with my invention, and, Fig. 2 is a similar view of one of the retaining pins or keys.

In carrying out my invention, I shall refer to the drawing in which similar reference characters designate corresponding parts throughout the several views and in which 1 indicates a metallic post of any desired shape in cross section, I having shown in the drawing, merely for convenience, a circular post, and said post is adapted to be anchored to any desired form of base, whereby the same may be positioned in the ground. Extending vertically on one side of the post are a plurality of laterally or horizontally disposed ears, or tongues 2, which are formed by striking up portions

of the post at regular intervals thereon, the space between each pair of tongues being adapted to receive a fence wire, and said tongues or ears are provided with alining openings 3 to receive a retaining means for the wires. As stated, the tongues 2 are formed on the post at regular intervals, as many being provided as desired, so that any number of wires may be passed between the same, and in order to retain the wires to the post, I provide a plurality of retaining pins or keys 4. These keys are adapted to extend through the alining openings 3 of said tongues, one key being extended through each pair of tongues, and the upper ends of said keys are bent at right angles, as shown at 5, whereby the keys will be retained in position when applied, and I have also provided means at the opposite ends of said keys for locking the same to the post. To this extent, the lower end of each key is bifurcated to form the spring arms 6 and 7, which arms are bulged centrally, as shown at 8, and the ends thereof brought tightly together, and in this form, the keys may be readily inserted in the openings 3, the bulged portions 8 being necessarily sprung through said openings and locking as the same is passed therethrough. The keys may thus be termed self-locking keys and when properly positioned, will not be liable to casual displacement. One of the greatest difficulties experienced in the use of a post of this character heretofore, has been in the use of an elongated pin or rod for retaining the wires to a post so that when it becomes necessary to remove the top wire, all the wires must be removed, in view of the fact that the rod must be removed through a vertical and upward movement. In this device, however, it will be seen that to remove any one of the wires, it is only necessary to remove one pin or key from the pair of tongues through which it extends, without interfering with the fastening of the other wires and the pin may be readily replaced with no difficulty whatsoever. Moreover, it will be seen, that the forming of the tongues or ears on the post in the manner described, does not weaken the post. It will still further be seen that by bifurcating the ends of the pins to form spring arms, which arms are bulged centrally, self-locking pins or keys will be formed, whereby when once positioned, they will not be casually displaced.

Although I have shown in the drawing a circular post with the tongues formed therein, it will be readily understood that any desired form of post may be provided, such 5 as a V or angular post and the tongues formed therein in a like manner, the same having an equal efficiency to that illustrated, without departing from the spirit of the invention. It will still further be seen that 10 I have provided a device which is very simple in construction, therefore inexpensive to manufacture and one which is extremely effective in operation.

What I claim is:—

15 A post of the character described, comprising a body portion having a plurality of laterally extending tongues struck there-

from and disposed in vertical alinement, said tongues being provided with alining openings, and a plurality of pins adapted 20 to be inserted through the openings in said tongues and having the upper ends thereof bent at right angles to limit the movement of the same, the lower ends of said pins being bifurcated to form spring arms and 25 said arms being bulged centrally to form self-locking means thereon.

In testimony whereof I hereunto affix my signature in the presence of two witnesses.

ELI M. BUECHELE.
